UNITED STATES PATENT OFFICE.

GLENN E. EDMUNDS, OF COLUMBUS, OHIO, ASSIGNOR TO THE BONNEY-FLOYD COMPANY, OF COLUMBUS, OHIO, A CORPORATION OF OHIO.

CAR.

Application filed December 13, 1921. Serial No. 522,080.

To all whom it may concern:

Be it known that I, GLENN E. EDMUNDS, a citizen of the United States, residing at Columbus, in the county of Franklin and State of Ohio, have invented certain new and useful Improvements in Cars, of which the following is a specification, reference being had therein to the accompanying drawing.

10 This invention relates to improvements in cars, particularly cars of the class used in and around industrial plants, and in coal mines for transporting the coal. The object is to provide a car which will embody all 15 of the advantageous features of the cars of the better class now in use, and will have the parts so constructed and arranged as to provide a maximum of cubical capacity without increasing the overall height and 20 width of the present cars now in use. As is well known, these cars, especially in coal mines, must travel in rooms or entries where the roof of the mine is comparatively low; and this condition prohibits increasing the 25 height of the cars above a certain fixed limit.

Another object of the invention is to provide a novel mounting for the wheels whereby through axles can be dispensed with, and 30 the wheels of each pair, transversely, will be independent of each other in respect to their revolutions and slippages.

Fig. 1 is a side elevation of a car embodying my improvements.

35 Fig. 2 is an end view of the same.

Fig. 3 is a bottom view of the same.

Fig. 4 is an end elevation showing the end opposite that shown in Fig. 2.

40 Figs. 5 and 6 are side elevations of the inner and outer frame parts, respectively, in which the wheels are mounted.

Figs. 7 and 8 show one of the wheels and its details of construction.

45 Fig. 9 shows one of the short axles upon which a wheel is mounted.

Fig. 10 is a perspective view of the truck structure detached.

The car, as an entirety, is composed of the body or load-holding part A, and the 50 wheeled truck B. The body is formed with a bottom C, the sides D, D, and the ends E and F.

55 The bottom of the body 2 has the two metallic side sills 1, 1, preferably channel beams, and the end bumper castings 2, 2

each having the side portions 3, 3, each of the latter overlapping one end of a side sill and being rigidly riveted or bolted thereto at 4, 4. The floor of the car is formed of wooden planks 5, 5 of suitable thickness, riveted or bolted to the bumper castings 2, 2 at 6, 6 and to the side sills at 7, 7 and 8, 8.

The sides of the body portion of the car comprise the uprights 9, 9, there being one 60 of these on each side at each end of the car and one on each side of the middle portion thereof. As shown these uprights are each formed to have the lower vertical portion 9^a, the outwardly and upwardly-extending portion 9^b, and the upper vertical portion 9^c. The lower portion 9^a of each upright is riveted or bolted to one of the side sills; and the side boards 10, 10 of the body are secured to the upper portions 9^b, 70 9^c of the uprights by means of rivets or bolts 11, 11, the uprights being provided with apertured ears 12, 12 through which the rivets or bolts pass.

The end E of the car is constructed to 80 serve as a door swingable outward around the upper hinge bar 13 which is mounted in vertical extensions of the uprights 9 at one end of the car. The end E comprises the planks 14, 14 securely fastened together by 85 the metal straps 15, the latter terminating in eyes 16; through which the hinge bar 13 passes that permits the vertical swinging movement of the door. At 17, 17 the wooden portions of the door are cut to conform 90 to the sides of the car to insure a snug fit when the door is in closed position. To retain the door in such position a latch, hereinafter described, is provided.

The wheeled truck B of the car comprises 95 the cross girts 18 and 19, the short sill-like elements 20 and 21, the axles 22 and the wheels 23.

As shown in Figs. 5, 6 and 10 the sills 20 and 21 are similar in design, one, however, being longer than the other for a purpose to be described. Each is formed, preferably, of cast metal and has the web portion 24 with the strengthening edge flanges 25. Each of the castings is formed with a recess 22^a near each end thereof to receive the end of an axle, and the strengthening web 25 is drilled at each side of each of the recesses 22^a, as at 26, to receive the pins or bolts that hold the axles in position.

An axle is shown detached in Fig. 9, it preferably being a hollow tube with plugs or closures 27 fitted in the ends, the interior of the axle being thus made a lubricant reservoir. Diametrically opposite apertures 27^a are drilled in the axle tube at each end to receive the bolts passing through the apertures 26 in the flanges 25 of the truck castings 20, 21, which hold the axle rigidly in place when the parts are assembled. A small aperture 28 is formed in each axle tube to furnish lubricant to its exterior surface. 23, 23 are wheels which may be of any preferred construction. As shown each comprises a hub 30, spokes 31, tread 32 and rail flange 33. To reduce rolling friction, as much as possible, roller bearings 34, suitably retained in place, are provided, they being interposed between the interior wall of the hub 30 and the axle 22.

The parts which carry the wheels at one side of the car are connected to the parts that carry the wheels on the other side by the frame girts 18 and 19. These are of channel metal and have their flanges turned downward. The longer girt 19 extends through apertures 35 in the inner sill bars 21, each of the latter being formed with a lug or boss 35^a to firmly fit between the flanges of the girt, the latter being secured by bolts at 37. It is also fitted at its ends in the outer sills 20, which have apertures 36, lugs 36^a and bolts 37^a to hold it to the sills.

The cross girts 18 are shorter than that at 19; they, at their ends, being fitted in cavities 22^b in the ends of the longer sill castings 21, the metal, here being formed with lugs 22^c that fit between the flanges of the cross girts 18 to which they are rigidly secured. The girts 18 and 19 are provided with apertures at suitable points along their central parts to receive the bolts which fasten the body and truck frame together.

It will be seen from the above that the car, as an entirety, comprises two separable elements, each complete within itself; one being the truck comprising the metallic cross girts and sills 20, 21 rigidly joined together with the axles and wheels; and the other being the body comprising the parts at the sides and ends, together with their metallic fastening devices. It will also be observed that the metallic truck element may be regarded as composed of a central part, and the wheel carrying frames at the extremities, rigid with the central part.

A coupler 40 is secured to the central part of the car at each end and is bolted to the bumper casting at points within the body portion of the car, but has its pin receiving portion extending through the end walls, as shown. Each of these couplers comprises the strap 45 which is secured at its inner end to the floor of the car and to the inwardly projecting tongue 46 of the bumper

casting by means of a bolt 47. This strap extends outward and upward for a short distance, and has a horizontal portion 48 projecting to a point near the outer edge of the bumper casting. It is apertured at 49 to receive and hold the lower end of the coupling pin 50 when it is inserted.

The central portion of the bottom of the end gate E is cut away to permit it to swing past the coupling strap 45. There is a latch 52 pivoted at one end 53 to the door, having its free end held in a loop in a strap 54. This latch, in its lowermost position is limited by the strap 54, slides along the upper surface of the coupler element 45 until it reaches a boss 55 formed thereon and having a sloping outer surface and a vertical inner surface. When the latch reaches the boss it is lifted by the sloping surface, passes over the top of the boss and then drops to its locked position behind the vertical surface. To release the door the latch 52 is lifted around the pivot 53 and the door may then be swung outward to dump the contents of the car. At 56 the latch is bent outward to provide a handle for convenient manipulation.

To further strengthen the sides of the car a U-shaped bracket 60 is bolted to the outer-wheel-supporting elements 20 and to the middle uprights 9 at points near the outer end of the inclined portion 9^b. These brackets strengthen, to a great extent, the side walls of the car and relieve the uprights of a great deal of strain which would be placed upon them without such reinforcement. It will be noted that the middle uprights 9, together with the straps 60, form arch members which transmit the expanding strains set up by the material in the body to both the outer and inner sill bars 20, 21, thus properly balancing the truck and enabling the sides of the body which are extended out over the wheels to be properly supported by the outer sill bars.

The advantages incident to a car such as I have described will be readily seen. By securing the cross girts 18 and 19 to the castings 20 and 21 at points below the upper edges of the latter I am enabled to materially deepen the body portion of the car without increasing its over-all height. In all other cars with which I am acquainted the horizontal positions of the cross girts have governed the height of the bottom of the car above the road bed. In some cases the bottom of the car has been relatively lowered by bending the cross girts downward at the sides of the car to permit such lowering, the truck portions remaining unchanged. But this greatly weakened the running gear. I accomplish the same result and at the same time produce a car with greatly increased strength and durability.

I dispense with the parts for separate

draw-bar construction which have heretofore been necessary, and sustain the draft strain practically entirely by the metallic framework at the base of the car.

5. What I claim is:

1. In a mine car, in combination: a car body having sides, bottom and ends rigidly secured together to form a unitary structure, a truck adapted to support said car body and comprising as a unitary structure, two pairs of separately formed sill castings, wheels carried by said sill castings, and a plurality of body-supporting cross girts rigidly connecting said sill castings, said car body and said truck being separable from each other as units.

2. A mine car comprising in combination: a car body having sides, bottom and ends rigidly secured together to form a unitary structure, a truck adapted to support said car body, said truck comprising a pair of inner and outer sill castings at each side thereof, axles removably secured to said sill castings, a plurality of wheels each carried independently by one of said axles, and a plurality of body-supporting cross girts rigidly connecting said sill castings, said car body and said truck being separable from each other as units, some of said girts extending between and secured only to the inner castings and at least one of said girts extending between the outer castings and secured thereto.

3. In a mine car, in combination: a truck comprising as a unitary structure two sill bars arranged at each side thereof and adapted to carry a plurality of independent wheels, a plurality of cross girts secured only to the two innermost sill bars, at least one cross girt extending beyond the wheels at each side of the car and secured to the two outermost sill bars, and a vertical brace on each of said outermost sill bars; and a car body having sides, bottom and ends rigidly secured together to form a unitary structure, uprights on said car body, the upper portion of said uprights being in line with the outer of said sill bars and the lower portion of said uprights being in line with the inner of said sill bars, said uprights being secured to the vertical braces on said outermost sill bars of the truck; whereby the body structure is separable from said truck structure.

4. A truck structure for mine cars comprising in combination: a pair of sill bars arranged at each side thereof, the inner of said sill bars having inturned marginal reinforcing flanges and outer of said sill bars having outturned marginal reinforcing flanges, a pair of axles removably secured to each pair of sill bars and disposed at each end thereof, wheels carried by said axles, and three cross girts extending transversely of and rigidly attached to and spacing the

inner of said sill bars, the middle one of said cross girts being of greater length than the others and rigidly attached to and spacing all of said sill bars.

5. A mine car comprising in combination: 70 a car body composed of sides, bottom and ends as a unitary structure, a truck for supporting said car body and comprising as a unitary structure, a pair of sill castings at each side thereof, the innermost of said castings of greater length than the outermost of said castings and relatively spaced therefrom, a pair of axles carried by each pair of sill castings and disposed at each end thereof, wheels mounted on said axles, and 75 three cross girts extending transversely of and rigidly attached to and spacing the inner of said sill castings, the middle one of said cross girts being of greater length than the others and rigidly connecting all of said 80 sill castings, said car body being separable from said truck.

6. In a mine car in combination: a car truck comprising as a unitary structure, two sill bars arranged at each side thereof and 90 relatively spaced, wheels carried by said sill bars, two cross girts rigidly connecting the inner of said sill bars, a third cross girt of relatively greater length extending through and rigidly connecting the inner of said sill 95 bars and the outer of said sill bars; and a car body comprising as a unitary structure, side sills adapted to be rigidly connected to the aforesaid side sills, uprights on said car body side sills, the upper portion of said 100 uprights being in line with the outer of said sill bars of the car truck and the lower portion of said uprights being in line with the inner of said sill bars, a flooring attached to said side sills and to said end 105 girts, side walls attached to said uprights, and end walls carried by said uprights, one of said end walls being swingable outwardly to serve as a gate; whereby said body structure is separable from said truck structure. 110

7. A mine car comprising in combination, 115 a truck, comprising, as a unitary structure, two pairs of sill castings, wheels carried by said sill castings, and a plurality of cross girts rigidly connecting said sill castings, a car body comprising, as a unitary structure, metallic side sills adapted to be rigidly connected to the aforesaid truck sills, metallic end sills adapted to be rigidly secured to the aforesaid car sills, uprights secured to said 120 car side sills, flooring attached to said side sills and to said end sills, side walls and end walls attached to said uprights, and coupler element secured, one to each of said end sills whereby drawbar strains are exerted upon 125 the aforesaid metallic parts of the car body.

8. In a mine car, in combination with a car body, a truck to which the body is adapted to be secured comprising as a unitary 130 structure separately formed sill castings ar-

ranged in pairs at opposite sides, a plurality of body-supporting cross girts extending between only the inner castings and connected thereto and an additional cross girt extending between the outer castings and connected thereto and to the inner castings, axles carried by said castings, and wheels positioned upon the said axles.

9. In a mine car, in combination with a car body, a truck to which the body is adapted to be secured comprising as a unitary structure separately formed sill castings arranged in pairs at opposite sides, a plurality of body-supporting cross girts extending between only the inner castings and connected thereto, an additional centrally disposed body-supporting cross girt extending between the outer castings and connected thereto and to the inner castings, axles carried by said castings and wheels positioned upon said axles.

10. In a mine car, in combination with a car body, a truck to which the body is adapted to be secured comprising as a unitary structure separately formed sill castings arranged in pairs at opposite sides, a plurality of cross girts extending between only the inner castings and connected thereto, an additional centrally disposed cross girt extending between the outer castings and connected thereto and to the inner castings, axles carried by said castings, and wheels positioned upon said axles, the inner sill castings being of greater length than the outer castings.

11. In a mine car, in combination with a car body, a truck to which the body is adapted to be secured comprising as a unitary structure, inner and outer separately formed sill castings arranged in pairs at opposite sides, a plurality of body-supporting cross girts extending between the castings and connecting the same together, some of said girts extending only between the inner castings, and at least one of said girts extending between the outer castings and connected thereto and to the inner castings, independent axles carried by each pair of castings and a plurality of wheels each carried independently by one of said axles between the members of each pair of castings.

12. In a mine car, in combination with a car body, a truck to which the body is adapted to be secured comprising as a unitary structure, inner and outer separately formed sill castings arranged in pairs at opposite sides, a plurality of body-supporting cross girts extending between the castings and connect the same together, some of said girts extending only between the inner castings and at least one of said girts extending between the outer castings and connected thereto and to the inner castings, and wheels carried between the castings at each side.

13. In a mine car, in combination, a car body having sides, bottom and ends rigidly

secured together to form a unitary structure, a truck adapted to support said car body and comprising as a unitary structure, two pairs of separately formed sill bars, wheels carried by said sill bars, and a plurality of body supporting cross girts rigidly connecting said sill bars, the cross girts being positioned below the top surfaces of said sill bars, and said car body and said truck being separable from each other as units.

14. A mine car comprising in combination, a car body having sides, bottom and ends rigidly secured together to form a unitary structure, a truck adapted to support said car body, said truck comprising a pair of inner and outer sill bars at each side thereof, axles removably secured to said sill bars, a plurality of wheels each carried independently by one of said axles, and a plurality of cross girts rigidly connecting said sill bars and positioned below the plane of the top surfaces of said bars.

15. In a mine car, in combination with a car body, a truck to which the body is adapted to be secured comprising, as a unitary structure, separately formed sill bars arranged in pairs at opposite sides, a plurality of body supporting cross girts extending between the inner bars and connected thereto, an additional body supporting cross girt extending between the outer bars and connected thereto and to the inner bars, all of said cross girts being positioned below the top surfaces of the inner bars, and means on said bars for receiving axles at opposite sides of the truck.

16. In a mine car, in combination with a car body, a truck to which the body is adapted to be secured comprising, as a unitary structure, separately formed sill bars arranged in pairs at opposite sides, a plurality of body supporting cross girts extending between only the inner bars and connected thereto, an additional body supporting cross girt between the two first mentioned cross girts extending between the outer bars and connected thereto and to the inner bars, all of said cross girts being positioned below the top surfaces of the inner bars, and means on said bars for receiving independent axles at opposite sides of the truck.

17. In a mine car, a truck adapted to support a car body comprising a pair of sill bars, a plurality of spaced body supporting cross girts extending between and connecting said bars, said girts being positioned below the top surfaces of the bars, a second pair of separately formed sill bars positioned on the outer sides of said first mentioned pair, and an additional cross girt extending between and connected at its ends to said second pair of bars and intermediate its ends to the inner pair.

18. In a mine car, a truck adapted to sup-

- port a car body comprising a pair of sill bars, a plurality of spaced body supporting cross girts extending between and connecting said bars adjacent their ends, said girts 5 being positioned below the top surfaces of the bars, a second pair of separately formed sill bars positioned on the outer sides of said first mentioned pair, and an additional cross girt extending between and connected at its 10 ends to said second pair of bars and intermediate its ends to the inner pair.
19. In a mine car, a truck adapted to support a car body comprising a pair of sill bars, a plurality of spaced body supporting cross girts extending between and connecting said bars, said girts being positioned below the top surfaces of the bars, and the bars having laterally extending supporting means for the ends of said girts, a second pair 15 of separately formed sill bars positioned on the outer sides of said first mentioned pair, and an additional cross girt extending between and connected to said second pair of bars and to the inner pair.
20. In a mine car, a truck adapted to support a car body comprising a pair of sill castings, a plurality of spaced body supporting cross girts extending between and connecting said castings adjacent their ends, 20 said girts being positioned below the top surfaces of the castings, and the castings having laterally extending supporting means for the ends of said girts, a second pair of 25 separately formed sill castings positioned on the outer sides of said first mentioned pair,
- and an additional cross girt extending between and connected at its ends to said second pair of castings and intermediate its ends to the inner pair.
21. In a mine or industrial car, a truck 40 frame comprising longitudinally extending sill bars arranged at opposite sides, and body supporting cross girts extending between the bars and connected thereto, said girts being positioned below the top surfaces of the bars 45 whereby a car body may be set down between the bars.
22. In a mine car, in combination with a car body, a truck frame comprising, as a unitary structure, sill bars arranged in pairs 50 at opposite sides, and a plurality of body supporting cross girts extending between the bars and connected thereto, said cross girts being positioned in substantially the same horizontal plane and below the top surfaces 55 of the sill bars, whereby the car body may be set down between the bars.
23. A truck structure for mine cars comprising two sill bars arranged at each side thereof and adapted to carry a plurality 60 of independent wheels, and a plurality of body supporting cross girts extending across the truck and connected to the bars at opposite sides, said cross girts being positioned below the top surfaces of the bars, at least 65 one of the cross girts extending beyond the wheels at each side of the car and secured to the two outermost sill bars.

In testimony whereof, I affix my signature.
GLENN E. EDMUNDS.
